UNITED STATES PATENT OFFICE.

KATHERINE FENNEMAN, OF CHICAGO, ILLINOIS.

WOMAN'S BURIAL-ROBE.

1,264,911.

Specification of Letters Patent.

Patented May 7, 1918.

Application filed January 12, 1918. Serial No. 211,466.

To all whom it may concern:

Be it known that I, KATHERINE FENNEMAN, a citizen of the United States, residing at Chicago, in the county of Cook and State 5 of Illinois, have invented certain new and useful Improvements in Women's Burial-Robes, of which the following is a specification.

This invention relates to burial robes, and 10 has reference more particularly to a burial robe designed and adapted for women, and to be used with half-couch caskets.

Among the objects sought by the invention are,—to provide a robe that shall combine 15 an artistic and elegant appearance with an economy of material, to provide a robe which shall do away with the unsightly separation at the waist line, and the unintentional display of cotton skirt, which is a frequent objection to the cheaper grades and styles of 20 burial robes now in vogue for half-couch casket use, to provide a robe which shall be practically adjustable to any size figure, and, generally, to improve the art of women's 25 burial robes in the directions of increased economy, practical adaptability to the purposes of such a robe, increased ease of application and use, and an exterior artistic and pleasing effect.

30 The structural features, mode of use, and advantages of my improved burial robe will be readily understood and appreciated by undertakers, and others familiar with the use of such garments, from the following 35 detailed description, taken in connection with the accompanying drawing wherein I have illustrated a practical and useful embodiment of the invention, and wherein—

Figure 1 is a front elevation of the complete garment, substantially as it appears on 40 the human form;

Fig. 2 is a rear or back elevation of the same;

Fig. 3 is a side elevation, viewed from the right of Fig. 1.

Fig. 4 is a horizontal section on the corresponding line of Fig. 1.

Fig. 5 is an enlarged vertical section through the intermediate or waist portion 50 of the garment, more particularly illustrating the means for drawing the garment in at the waist line to fit the figure.

My improved burial robe is a one-piece garment; preferably, and in the form herein 55 shown, of three-quarter length. It comprises essentially an inner portion or lining

extending from the neck to the waist line and for the full length of the sleeves, which is of sufficiently heavy fabric to give form to the garment, and terminates at the waist 60 line in a wide hem or draw-string pocket, and an outer or dress portion, preferably of silk, which comprises a one-piece waist and short skirt that is stitched to the hem or draw-string pocket at the upper and lower 65 edges of the latter, and preferably shirred at that point. The lining and the outer or dress cover are both made of substantial width at the waist line, and a draw-string disposed in the draw-string pocket enables 70 the waist portion of the garment to be drawn in so as to present a neat and graceful fit on either stout or thin figures.

Turning now to a more detailed description of the garment, by reference to the accompanying drawing, 6 designates the front portion, 7 the rear portion, and 8 the sleeve portions of the body or lining of the garment, which is preferably made of heavy muslin or light flannel cloth. The rear portion 7 of this lining has a central vertical opening 9 in the back extending from the neck to the waist line, and at its lower end the lining portion of the garment is formed with a draw-string loop or pocket which may 85 be formed by a broad hem. As shown in Fig. 5, this pocket is preferably formed by stitching to the outer side of the lining a strip or tape 10, the lower edges being turned upwardly and inwardly and stitched together 90 at 11, and the upper edge of the tape or strip 10 being turned downwardly and stitched to the body 6, as indicated at 12. By this construction a comparatively wide holder or pocket 13 is formed which receives a draw-string or tape 14, the ends of which extend through and beyond the two ends of the pocket at the lower end of the back opening 9.

The outer or dress portion of the garment, which, as above stated, is preferably made of silk, comprises integral waist and short-skirt portions designated by 15 and 16, respectively, and sleeve portions 17 that cover the lining sleeve portions 8, and are 105 stitched to the latter at the shoulders and wrists, as indicated at 18 and 19, respectively. Substantial economy of the expensive outer or dress material is effected, without detriment to the artistic and elegant appearance of the robe when in service, by omitting the usual back portions of 110

the waist and skirt, as is indicated in Figs. 2 and 3. That is to say, the waist portion 15 covers and conceals only the front portion 6 of the lining, while the skirt portion 16 is made of only sufficient length to extend slightly below the lower edge of the casket cover opening or panel. At its longitudinal edges the skirt portion 16 preferably extends rearwardly or backwardly to 10 a slight extent, as indicated at 16' in Fig. 2, so as to avoid any accidental or careless exposure of the undergarment at the sides of the hips. This one-piece waist and skirt is stitched to the outer surface of the draw-string pocket 13 of the lining at the points 15 11 and 12, and is preferably Shirred where it covers the said pocket so as to give it both an attractive and artistic appearance at the waist line, and also a considerable degree of transverse elasticity or flexibility, by which is meant adaptability to fit widely varying sizes of waist measure. When the garment has been draped on the figure the waist line is drawn in by manipulating the 20 draw-string 14, the projecting ends of which are tied at the rear in a knot, such as is indicated at 20 in Fig. 2. The back opening 9 is closed by any suitable or convenient fasteners, and when the robe has been properly applied to and draped upon the figure, and the latter disposed in the usual recumbent position in the casket, a fully and elegantly dressed appearance or effect is obtained, and particularly is the unsightly gap 25 at the waist line avoided. Since the garment may be drawn in or gathered to any extent in the back without display of that portion when in use, it may be made of sufficient width to fit the stoutest figures, and at 30 the same time be adaptable to the thinnest figures, and all intermediate sizes of waist measurement, thereby practically enabling it to be made in a standard or stock size. The elimination of the back outer dress portion of the garment contributes materially 35 to economy of cost.

It is evident that the garment as shown and described may be varied in minor details without substantially changing its 40 structural characteristics, or sacrificing the advantages which result therefrom. Hence, I do not limit the invention to the precise embodiment herein selected for purposes of illustration, but reserve all such variations

and modifications as fall within the spirit 55 and purview of the appended claims.

I claim:

1. A woman's burial robe comprising a body or lining of waist length and relatively heavy material, and formed with a draw-string pocket at its lower edge, an outer or dress covering of relatively light, thin material including integral waist and skirt portions stitched at the waist line to said draw-string pocket, and a draw-string 65 in said pocket.

2. A woman's burial robe comprising a body or lining of waist length and relatively heavy material divided in the back and formed with a draw-string pocket at its 70 lower edge, an outer or dress covering of relatively light, thin material including integral waist and skirt portions stitched at the waist line to said draw-string pocket, and a draw-string in said pocket 75 having its ends extending beyond the meeting ends of the latter.

3. A woman's burial robe comprising a body or lining of waist length and relatively heavy material divided in the back 80 and formed with a draw-string pocket at its lower edge, an outer or dress covering of relatively light, thin material including integral front waist and skirt portions stitched at the waist line to said draw-string 85 pocket, said waist and skirt portions terminating laterally substantially at the median side lines of the garment, and a draw-string in said pocket having its ends extending beyond the meeting ends of the latter. 90

4. A woman's burial robe comprising a body or lining of waist length and relatively heavy material having a substantially central, vertical opening in the back, and formed with a draw-string pocket at its 95 lower edge, an outer or dress covering of relatively light, thin material including integral front waist and short skirt portions gathered at the waist line and stitched to the upper and lower edges of said draw-string pocket, said waist and skirt portions terminating laterally substantially at the median side lines of the garment, and a draw-string in said pocket having its ends extending beyond the meeting ends of the 105 latter.

KATHERINE FENNEMAN.
